Primary Examiner — Jennifer Rivard*Assistant Examiner* — Alison M Ofstun(74) Attorney, Agent, or Firm — Fross Zelnick Lehrman & Zissu, P.C.; Lawrence E. Apolzon, Esq.(57) CLAIM

The ornamental design for a lipstick sheath, as shown and described.

DESCRIPTION

FIG. 1 is a front perspective view of a lipstick sheath showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an exploded perspective view thereof.

In the drawings, the broken lines illustrate portions of the article which form no part of the claimed design.

1 Claim, 5 Drawing Sheets
